UNITED STATES PATENT OFFICE.

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed November 16, 1925, Serial No. 69,228. Renewed September 15, 1926.

This invention relates to mining machines and more particularly to mining machines of the type commonly known as the continuous cutter coal mining machines which are adapted to be moved laterally across the wall of a mine to cut a horizontal kerf thereunder. More specifically, my invention relates to machines of the class described especially adapted for use in thin seams of coal, and has for its principal object to produce an improved construction and arrangement of parts for this purpose.

Other objects of the invention will appear from time to time as the description proceeds.

The invention consists in the combination, construction, and arrangement of parts as will hereinafter be described in connection with the accompanying drawings, and more particularly defined in the appended claims.

In these drawings:

Figure 1 is a plan view of the machine, with the gear housing cover removed to show the parts thereunder;

Figure 2 is a right side elevation of the machine;

Figure 3 is an enlarged sectional view taken through Figure 1 on line 3—3 thereof;

Figure 4 is an enlarged detail plan view of the front of the machine with the gear housing cover removed, and parts omitted;

Figure 5 is a sectional view taken through Figure 4 on line 5—5 thereof;

Figure 6 is an enlarged sectional view taken on line 6—6 of Figure 4;

Figure 7 is a plan view of the rearward portion taken on line 7—7 of Figure 4 of the machine, with parts broken away to show details of a sweeping device for clearing away the slack cuttings; and

Figure 8 is a side elevation of the rearward portion of the machine with parts broken away to show the sweeping mechanism.

Referring now to the details of the drawings:

My invention is shown as applied to a mining machine having a main frame A, with a cutting element 1 projecting therefrom. This cutting element is preferably provided with an endless cutter chain of the usual pattern, which is driven by a motor B to cut a horizontal kerf in the mine wall as the machine is moved by suitable draft devices in the ordinary and well

known manner of machines of this type. Figure 1 shows the arrangement of the machine and control ropes during the normal cutting operation across the working face. A rope 2 is adapted to be wound on a drum 3, mounted on the left side of the machine frame A near the forward end thereof and is rotatable upon a transverse axis. The rope passes from said drum over a pulley 4 adjacent the front end of the frame, and thence to a suitable anchor near the working face along which the machine is to be moved. A second rope 6 is anchored at the opposite end of the working face and is arranged over suitably arranged pulleys 7 and 8 at the side and rear end of the machine frame, to a second drum 9, at the right side of the machine and also rotatable on a transverse axis. The arrangement is such that in the normal cutting position illustrated in this figure, the rope drum 3 is connected to the motor B by driving mechanism which will be hereinafter described. The opposite drum 9 is disconnected from the driving mechanism, and during the cut across the face, is released at a rate substantially the same as the rate of take up on the rope 2, by means of an adjustable friction band device 10 on the drum 9. The purpose of the rope 6 during this part of the cutting movement is to restrain the movement of the rear end of the machine, and maintain the proper angular relation of the cutter bar to the working face.

As will hereinafter more fully appear, means are also provided for reversing the normal functions of the two drums above described, whereby drum 9 may have a driving connection with the motor, and the other drum 3 may be released through a friction device 11 similar to the friction device 10 above pointed out.

The main elements of the driving mechanism for the two feed rope drums 3 and 9 will now be described:—

A shaft 12 having suitable bearing supports 13 and 14 is arranged longitudinally within a main gear housing 15 forwardly of the motor. Said motor is preferably of the electric type, having a horizontally disposed armature shaft 16 provided with an armature pinion 17, at its forward end meshed with gear 18 keyed on the rear end of the longitudinal shaft 12. Adjacent the forward end of said longitudinal shaft and

mounted concentric thereon is a planetary reduction gearing device consisting of a sun gear 20 keyed on the longitudinal shaft and meshed with a plurality of planetary gears 21, 21, carried on a cage 22 loosely mounted for rotation on the shaft 12. Said cage is provided with a hub 23, having a pinion 24 with integral sleeve 25 feathered thereon for limited longitudinal movement. A casing 10 26 surrounds the cage 22 and planetary gears 21, 21, and has a hub portion 29 loosely mounted for rotation upon the hub 25 of the pinion 24. Said hub has exterior bearing in a bearing support 29 integral with the gear 15 housing frame 15. The casing 26 is normally restrained from rotation by means of a suitable friction band 32 which is actuated by controlling means comprising the usual tightening lever system (not shown) 20 connected with an actuating arm 33, a bell crank lever 34, link 35 and control rod 36 extending rearwardly at one side of the motor casing 6, as best shown in Figures 4 and 7.

25 This arrangement of the planetary gearing affords a driving connection wherein the cage 22 is driven at a reduced speed when the casing 26 is restrained from rotation by means of the friction band 32. By manipulation of the friction band further reduction in driving speed may be afforded when desired. The principal advantage of the friction control of the planetary however, is that afforded in case of unusual and excessive 30 loads upon the feed mechanism as for instance when unusually heavy cutting is encountered in which case the tension of the friction band on the casing 26 is such as to permit the latter to slip and thereby release 35 the load somewhat and minimize the danger of breakage of parts of the gear train.

40 The pinion 24 which is rotatable with the cage 22 at reduced speed as aforesaid, is meshed with a gear 39 on a stub shaft 40 at one side of and parallel to the longitudinal shaft 12. The gear 39 is adapted to have selective driving engagement with the shaft 40 through a sliding clutch member 41, as herein shown comprising a longitudinally 45 shiftable collar 42 keyed on said shaft and having an enlarged portion 43 provided with internal teeth adapted to engage with external gear teeth 44 on the end of the hub 39 integral with gear 39, as shown in Figure 4. A cylinder clutch device 45 is mounted on the shaft 12 to provide selective connection between the gear pinion 24 and a shaft 47 supported co-axially with the shaft 12 at the forward end thereof in suitable 50 bearings 48, 48. The shaft 47 also has driving connection with the stud shaft 40 through gears 50 and 51, keyed on the forward ends of the respective shafts. An interlocking gear shift arrangement is provided for actuating the two clutches 41 and

45, so while the two are engaged a driving connection is completed from the pinion 24 through gear 39, shaft 40 and gears 51 and 50 to shaft 47 at a relatively slow speed, the hubs 45 being disengaged in this position. In the other position, the clutches 45 and 41 are disengaged, in which case the shaft 47 rotates with the pinion 24. The interlocking connection for clutches 41 and 45 comprises an arm 55, pivoted at 56 and 70 having direct connection at its end with a shifter yoke 57 on clutch member 42 and a link 58 connected with clutch yoke 59 on clutch member 45.

80 A worm 60 is carried on the shaft 47 and meshed with a worm gear 61 keyed on a collar 62 arranged on a transverse axis. This collar has a sleeve 63 extending therethrough, which sleeve is keyed on a shaft 64. The sleeve 63 and shaft 64 are shiftable longitudinally within the collar 62 to afford selective driving connection with either of a pair of gear pinions 65 and 66 arranged at opposite sides of the main frame and adapted to afford driving engagement respectively 85 with the feed drums 9 and 3, as shown in Figure 6. For this purpose, the opposite ends of the collar 62 are provided with clutch jaws 67 and 68, while the opposite ends of the sleeve 63 are provided with coacting clutch jaws 69 and 70. The adjacent ends of gear pinion member 65 are also provided with coacting clutch jaws 71 and 72. The arrangement is such that when in neutral position, as shown in Figure 6, the clutch jaw 69 at the left side of the machine adjacent the pinion member 65 is midway between the clutch jaws 71 of said pinion member and the adjacent clutch jaws 67 of the collar 62, and similarly, the clutch jaws 70 at the right hand side of the machine adjacent the pinions 66 are midway between the clutch jaws 72 of said pinion member and clutch jaws 68 of the collar 62.

90 When the shaft 64 and sleeve 63 are shifted in one direction however, a driving connection will be afforded by the collar 62 and one of the pinion members 65 or 66, as for instance if the direction of the shift is 95 toward the left, the clutch jaws 69 will become engaged with clutch jaws 71, while jaws 70 will be engaged with jaws 68. Similarly, if the collar 69 is shifted in the opposite direction, jaws 70 will become disengaged with jaws 68 and become directly 100 engaged with jaws 72. This arrangement, therefore, affords an interlocking shifting arrangement so that only one of the pinion members 65 and 66 may be driven at one time. The pinion members 65 and 66 are 105 meshed respectively with gears 75 and 76 of the drums 9 and 3.

110 As pointed out in connection with the normal operation of a machine of this class, it is desirable to drive one of the feed rope 115

drums so as to wind the cable thereon, while the other drum is being released under suitably controlled friction retarding means, so as to unwind the cable extending from the rear end of the frame and acting as a counterbalancing or retarding device to maintain the proper angular relation to the working face. In the embodiment illustrated the arrangement is such that the functions of the drums are reversible so that either drum may be driven so as to wind the cable thereon, but when not being driven, each drum is provided with a frictional retarding device to control the winding of the cable therefrom. This construction of the drums 3 and 9, in connection with the provision of driving connections associated with the respective gears 75 and 76, and the friction devices 10 and 11 will now be described in detail.

In the construction herein shown the drums 3 and 9 are identical, the respective drums or rope retaining members 3 and 9 having spur gears 75 and 76 carried thereby, and adjacent friction surfaces for engagement by brake bands 10 and 11 respectively. The drums are rotatable on transverse axes on opposite sides of the frame, adjacent the forward end thereof, as herein shown said drums being carried on transversely disposed stub shafts 170 and 171 having a common axis. Control means for the brake bands 10 and 11 may comprise any suitable arrangement, such as the common bell crank lever device illustrated, which extends toward the rear of the machine and is actuated by the arm 33.

Referring now to the cutter chain and the driving connections therefor, said chain comprises a series of blocks 110 and connecting straps 111, of the usual form, moving in guides 112 formed in the cutter bar 1. Said cutter bar is supported on the frame 15 by a pair of clamps 115, 116. The cutter chain passes about a sprocket 117 located near the rear end of the cutter bar and within a housing or passageway formed beneath the gear housing 15 between the side walls 119 and 118 and the base plate 120 upon which the machine rests or slides upon the mine floor.

The sprocket 117 is keyed on a shaft 125 having bearing in a downwardly projecting stud 127 formed integrally with the main frame 15, and having a bevel gear 128 keyed at its upper end meshing with a bevel pinion 129 loosely mounted on longitudinal shaft 12. A clutch device 130 affords selective driving connection between shaft 12 and bevel pinion 129. In the form shown said clutch consists of a sliding clutch member 131 having exterior teeth 132 adapted to engage with internal gear teeth 133 on one end of the hub 134 integral with the bevel pinion 129. The sliding clutch mem-

ber 131 is shiftable by a yoke 135 on shaft 136 arranged transversely of the machine and having controlling means therefor consisting of a lever arm 136 connected to a control rod 137 extending rearwardly along one side of the motor casing *b* as best shown in Figures 4 and 7.

Referring now to the disposition of the cuttings brought rearwardly by the cutter chain, the specific form of machine illustrated is preferably provided with a motor of reversible type so as to permit the cutter chain to be driven in either direction. Accordingly, the cuttings will be brought rearwardly on one side or the other of the cutter chain and be deposited along the passageway formed between the cutter bar and the side walls 118 and 119 but with the greatest tendency of the cuttings to be discharged and thrown rearwardly by the cutter chain as it passes about the sprocket 117. This sprocket forms in effect a fixed guide in which the direction of movement of the cutter chain is changed.

One of the objects of the present invention is to provide, in combination with a mining machine constructed in accordance with the foregoing, a means for discharging these cuttings as they are brought rearwardly into the housing surrounding the cutter arm and the cutter chain sprocket, so that the accumulations of cuttings will not clog the machine or be carried back by the cutter chain into the kerf. As shown in Figures 2 and 8, the motor *B* is contained in a motor housing *b*, this housing being somewhat higher than the base plate 120, upon which the machine rests. This arrangement produces a low passageway 122 extending rearwardly below the motor casing and communicates with the larger passageway formed in front of the motor casing and beneath the gear housing 15, above the cutter chain. Manifestly, in order to reduce the height of the entire machine, as low as possible, commensurate with the successful operation thereof, it is desirable to reduce the height of the passageway 122 to a minimum.

In the present invention I provide an improved means for ejecting the cuttings from adjacent the rear end of the cutter chain through the rear and side of the machine beneath the motor, comprising an oscillating sweep or arm, which requires a minimum of height for its successful operation and is capable of handling a large amount of cuttings.

This sweep or arm forms the subject matter of a companion application bearing Serial Number 56,151, filed September 14, 1925, and will now, together with its driving connections, be described.

The sweep or arm 140 is adapted to have oscillating movement in a substantially hori-

zontal plane along the base plate 120. In the preferred form shown this sweep is keyed to a shaft 141 having pivotal bearing on a vertical axis near the rear and to one side 5 of the main motor housing *b* so that the sweep is adapted to oscillate through an arc of approximately 90 degrees, with the extreme rearward position thereof coinciding substantially with the rear margin of the 10 bottom plate 120 while its extreme position in the opposite direction is substantially coincident with the side margin of the bottom plate 120. The sweep may be suitably driven by the motor B, in the form shown, 15 the operating connections comprising a lever arm 145 on the upper end of the shaft 141 and connected with a link 146 to a lever arm 147, pivotally mounted at 148 in the gear housing 15 forwardly of the motor 20 casing *b* as best shown in Figures 4 and 7. The opposite arm of the lever 147 is connected with a link 149 to a crank arm 150 on a vertically disposed shaft 151 having a worm gear 152 thereon meshed with a 25 worm 153 loosely mounted on the horizontal shaft 40 and being integral with gear 39 which is driven by the gear 23 as heretofore set forth.

With this arrangement the sweep 140 is 30 swung angularly at reduced speed so as to remove the cuttings alternately toward the side and rear of the machine and discharge them as rapidly as they are brought back by the cutter chain.

35 As a further improvement I construct the end portion of the sweep so as to be extended at one portion of its movement and retracted at another thereby accommodating itself more approximately to the shape of 40 the discharge passage and cooperating with the cutter chain as it passes about the driving sprocket 117 and thus assist in discharging the cuttings therefrom in the most efficient manner. In the form shown this means 45 comprises a telescoping end portion 157 carrying a lug 158 engaging a fixed guide means 159 and 160, herein shown as flanged pieces secured to the under surface of the motor casing *b*. The outer end portion 157 50 is provided with a guide rod 163 carrying a web 164 at the inner end thereof and extending in a cylinder 165. A tension spring 166 is secured in said cylinder between the web 164 and a fixed shoulder 167 in said 55 cylinder, the arrangement being such that the rod 163 and web 164 have a tendency to force the end portion 157 outwardly as shown in Figure 7. When the sweep is swung outwardly to its extreme position however, 60 as shown in dotted lines in this figure, the lug 158 engages either of the flanges 159 or 160 to contract the telescoping end portion 157 thus varying the length of the entire sweep to accommodate it to the size of the 65 passage and thus eliminate interference with

the moving cutter chain as the sweep swings near the latter.

One of the main advantages of the construction above described is the provision of an improved form of mining machine and cuttings removing means so that the entire height of the machine may be reduced to a minimum, it being understood that the motor *b* usually forms the largest element on such machines and therefore to a large 70 degree determines the permissible height of the machine. Continuous cutter machines for mining have heretofore been produced in which the motor casing rests directly upon the mine floor but in such instances 75 the cuttings have been discharged through one side of the machine open along the entire length of the cutter arm for this purpose. It will be observed from the construction illustrated and above described that the lower peripheries of the power drums 3 and 9 project downwardly a considerable distance so as to make it impossible to provide a discharge passage along the full length of either side of the machine. I consider it 80 novel therefore to produce a machine wherein the driving connections are provided with two drums arranged at opposite sides of the machine in position to afford readily reversible draft connections as described but 85 with suitable cuttings discharge means located rearwardly of the cutter chain and the cable drums and permitting the arrangement of the lower boundary of the motor to be at a much lower level than the top of the 90 cutter bar.

Although I have shown and described one embodiment of my invention it will be understood that the construction and arrangement of the various parts may be altered 105 without departing from the spirit and scope of the invention. Furthermore, I do not wish to be construed as limiting myself to the specific construction illustrated except as particularly defined and limited in the 110 appended claims.

I claim as my invention:

1. In a mining machine, a frame, a cutter bar extending forwardly from said frame and having a cutter chain mounted thereon, 115 a motor at the rear end of said frame, a longitudinal shaft disposed above said cutter bar and connected with said motor, feed operating mechanism mounted on said frame forwardly of said motor, a planetary gear reduction device mounted concentrically 120 with said longitudinal shaft and operatively connected with said feed operating mechanism for driving the same at reduced speed, a driving sprocket for said cutter chain disposed on a vertical axis between said planetary gear and said motor, and gearing connections between said longitudinal shaft and 125 said driving sprocket.

2. In a mining machine, a frame, a cutter 130

- bar extending forwardly from said frame and having a cutter chain mounted thereon, a motor at the rear end of said frame, a longitudinal shaft disposed above said cutter bar and connected with said motor, a pair of feed operating mechanisms mounted on opposite sides of said frame forwardly of said motor, a planetary gear reduction device mounted concentrically with said longitudinal shaft and operatively connected with said feed operating mechanisms for selectively driving either thereof at reduced speed, a driving sprocket for said cutter chain disposed on a vertical axis between said planetary gear and said motor, and gearing connections between said longitudinal shaft and said driving sprocket. 5
3. In a mining machine, a frame, a cutter bar extending forwardly from said frame and having a cutter chain mounted thereon, a motor at the rear end of said frame, a longitudinal shaft disposed above said cutter bar and connected with said motor, a pair of feed operating mechanisms mounted on opposite sides of said frame forwardly of said motor, a planetary gear reduction device mounted concentrically with said longitudinal shaft, means arranged forwardly of said planetary gear and affording operative connections with said feed operating mechanisms for selectively driving either thereof at reduced speed, a driving sprocket for said cutter chain disposed on a vertical axis between said planetary gear and said motor, and gearing connections between said longitudinal shaft and said driving sprocket. 10
4. In a mining machine, a frame, a cutter bar extending forwardly from said frame and having a cutter chain mounted thereon, a motor at the rear end of said frame, a longitudinal shaft disposed above said cutter bar and connected with said motor, a pair of feed operating mechanisms rotatable on transverse axes on opposite sides of said frame forwardly of said motor, a gear reduction means on said frame between said feed operating mechanisms, said gear reduction means being driven by said longitudinal shaft and operatively connected with said feed operating mechanisms for selectively driving either thereof at reduced speed, a driving sprocket for said cutter chain disposed on a vertical axis between said planetary gear and said motor, and gearing connections between said longitudinal shaft and said driving sprocket. 15
5. In a mining machine, a frame, a cutter bar extending forwardly from said frame and having a cutter chain mounted thereon, a motor at the rear end of said frame, a longitudinal shaft disposed above said cutter bar and connected with said motor, feed operating mechanisms mounted on said frame forwardly of said motor comprising winding means arranged on a transverse axis having a flexible feeding means connected therewith, the peripheries of said winding means extending below the top of said cutter bar, a planetary gear reduction device mounted concentrically with said longitudinal shaft and operatively connected with said feed operating mechanism for driving the same at reduced speed, a driving sprocket for said cutter chain disposed on a vertical axis between said planetary gear and said motor, and gearing connections between said longitudinal shaft and said driving sprocket. 20
6. In a mining machine, a frame, a cutter bar extending forwardly from said frame and having a cutter chain mounted thereon, a motor at the rear end of said frame, a longitudinal shaft disposed above said cutter bar and connected with said motor, feed operating mechanisms mounted on said frame forwardly of said motor comprising a pair of winding drums arranged on a transverse axis having flexible feeding means connected therewith, the peripheries of said drums extending below the top of said cutter bar, a planetary gear reduction device mounted concentrically with said longitudinal shaft and operatively connected with said feed operating mechanism for driving the same at reduced speed, a driving sprocket for said cutter chain disposed on a vertical axis between said planetary gear and said motor, and gearing connections between said longitudinal shaft and said driving sprocket. 25
7. In a mining machine, a frame, a cutter bar extending forwardly from said frame and having a cutter chain mounted thereon, a motor at the rear end of said frame, a longitudinal shaft disposed above said cutter bar and connected with said motor, feed operating mechanism mounted on said frame forwardly of said motor comprising winding means arranged on a transverse axis having flexible feeding means connected therewith, the peripheries of said winding means extending below the top of said cutter bar on opposite sides thereof, a planetary gear reduction device mounted concentrically with said longitudinal shaft and operatively connected with said feed operating mechanism for driving the same at reduced speed, a driving sprocket for said cutter chain disposed on a vertical axis between said planetary gear and said motor, and gearing connections between said longitudinal shaft and said driving sprocket. 30
8. In a mining machine, a frame, a cutter bar extending forwardly from said frame and having a cutter chain mounted thereon, a motor at the rear end of said frame, a longitudinal shaft disposed above said cutter bar and connected with said motor, feed operating mechanism mounted on said frame forwardly of said motor comprising winding means arranged on a transverse axis having flexible feeding means connected therewith, the peripheries of said winding means extending below the top of said cutter bar on opposite sides thereof, a planetary gear reduction device mounted concentrically with said longitudinal shaft and operatively connected with said feed operating mechanism for driving the same at reduced speed, a driving sprocket for said cutter chain disposed on a vertical axis between said planetary gear and said motor, and gearing connections between said longitudinal shaft and said driving sprocket. 35

- winding means arranged on a transverse axis having flexible feeding means connected therewith, the peripheries of said winding means extending below the top of said cutter bar, and a planetary gear reduction device mounted concentrically with said longitudinal shaft and operatively connected with said feed operating mechanism for driving the same at reduced speed.

9. In a mining machine, a frame, a cutter bar extending forwardly from said frame and having a cutter chain mounted thereon, a motor at the rear end of said frame whose lower margin is below the top of said cutter bar, a longitudinal shaft disposed above said cutter bar and connected with said motor, a pair of feed operating mechanisms mounted on opposite sides of said frame forwardly of said motor, a planetary gear reduction device mounted concentrically with said longitudinal shaft and operatively connected with said feed operating mechanism for driving either at reduced speed, a driving sprocket for said cutter chain disposed on a vertical axis between said planetary gear and said motor, and gearing connections between said longitudinal shaft and said driving sprocket.

10. In a mining machine, a frame, a cutter bar extending forwardly from said frame and having a cutter chain mounted thereon, a motor at the rear end of said frame whose lower margin is below the top of said cutter bar, a longitudinal shaft disposed above said cutter bar and connected with said motor, a pair of feed operating mechanisms mounted on opposite sides of said frame forwardly of said motor, a planetary gear reduction device mounted concentrically with said longitudinal shaft and operatively connected with said feed operating mechanism for driving either at reduced speed, a driving sprocket for said cutter chain disposed on a vertical axis between said planetary gear and said motor, and gearing connections between said longitudinal shaft and said driving sprocket.

11. In a mining machine, a frame, a cutter bar extending forwardly from said frame and having a cutter chain mounted thereon, a motor at the rear end of said frame whose lower margin is below the top of said cutter bar, a longitudinal shaft disposed above said cutter bar and connected with said motor, a pair of feed operating mechanisms mounted on opposite sides of said frame forwardly of said motor, a gear reduction device mounted concentrically with said longitudinal shaft and operatively connected with said feed operating mechanism for driving either at reduced speed, a driving sprocket for said cutter chain disposed on a vertical axis between said reduction gear and said motor, and gearing connections between said longitudinal shaft and said driving sprocket.

12. In a mining machine, a frame, a cutter bar extending forwardly from said frame and having a cutter chain mounted thereon, a motor at the rear end of said frame whose lower margin is below the top of said cutter bar, a longitudinal shaft disposed above said cutter bar and connected with said motor, a pair of feed operating mechanisms mounted on opposite sides of said frame forwardly of said motor, and a planetary gear reduction device mounted concentrically with said longitudinal shaft and operatively connected with said feed operating mechanism for driving either at reduced speed.

13. In a mining machine, a frame, a cutter bar extending forwardly from said frame and having a cutter chain mounted thereon, a motor at the rear end of said frame, a longitudinal shaft disposed above said cutter bar and connected with said motor, feed operating mechanisms mounted on transverse axes at opposite sides of said frame forwardly of said motor, a planetary gear reduction device mounted concentrically with said longitudinal shaft, a transversely disposed shaft forwardly of the axis of said feed mechanism having clutch mechanism thereon for selectively engaging either of said feed operating mechanisms with said gear reduction device, a driving sprocket for said cutter chain disposed on a vertical axis between said planetary gear and said motor, and gearing connections between said longitudinal shaft and said driving sprocket.

14. In a mining machine, a frame, a cutter bar extending forwardly from said frame and having a cutter chain mounted thereon, a motor at the rear end of said frame, a longitudinal shaft disposed above said cutter bar and connected with said motor, feed operating mechanisms mounted on transverse axes at opposite sides of said frame forwardly of said motor, a planetary gear reduction device mounted concentrically with said longitudinal shaft, and a transversely disposed shaft forwardly of the axis of said feed mechanism having clutch mechanism thereon for selectively engaging either of said feed operating mechanisms with said gear reduction device.

15. In a mining machine, a frame, a cutter bar extending forwardly from said frame and having a cutter chain mounted thereon, a motor at the rear end of said frame, a longitudinal shaft disposed above said cutter bar and connected with said motor, feed operating mechanisms mounted on opposite sides of said frame and forwardly of said motor comprising drums having cable wound thereon, a planetary

- gear reduction device mounted concentrically with said longitudinal shaft, a transverse shaft disposed forwardly of the axis of said feed operating mechanisms having 5 clutch mechanism thereon for selectively engaging either of said drums with said planetary device, friction devices on said drums for retarding their unreeling speed, a driving sprocket for said cutter chain disposed 10 on a vertical axis between said planetary gear and said motor, and gearing connections between said longitudinal shaft and said driving sprocket.
16. In a mining machine, a frame, a cutter bar extending forwardly from said frame and having a cutter chain mounted thereon, a motor at the rear end of said frame, a longitudinal shaft disposed above said cutter bar and connected with said motor, feed 15 operating mechanisms mounted on opposite sides of said frame and forwardly of said motor comprising drums having cable wound thereon, a planetary gear reduction device mounted concentrically with said longitudinal shaft, a transverse shaft disposed forwardly of the axis of said feed operating mechanisms having clutch mechanism thereon for selectively engaging either of said drums with said planetary device, and friction devices on said drums for retarding their unreeling speed.
17. In a mining machine, a frame, a cutter bar extending forwardly from said frame and having a cutter chain mounted thereon, a motor at the rear end of said frame, a longitudinal shaft disposed above said cutter bar and connected with said motor, feed operating mechanisms mounted on said frame forwardly of said motor, a planetary gear 20 reduction device mounted concentrically with said longitudinal shaft and operatively connected with said feed operating mechanisms for driving the same at reduced speed, a driving sprocket for said cutter chain disposed on a vertical axis between said gear reduction means and said motor, and gearing connections between said longitudinal shaft and said driving sprocket.
18. In a mining machine, a frame, a cutter bar extending forwardly from said frame and having a cutter chain mounted thereon, a motor at the rear end of said frame, a longitudinal shaft disposed above said cutter bar and connected with said motor, feed operating mechanisms mounted on said frame forwardly of said motor, a planetary gear reduction device mounted concentrically with said longitudinal shaft and operatively connected with said feed operating mechanisms for driving the same at reduced speed, a driving sprocket for said cutter chain disposed on a vertical axis between said planetary gear and said motor, gearing 30 connections between said longitudinal shaft and said driving sprocket, and cuttings expulsion means beneath said motor and driven through said planetary gear.
19. In a mining machine, a frame, a cutter bar extending forwardly from said frame and having a cutter chain mounted thereon, a motor at the rear end of said frame, a pair of feed operating mechanisms mounted on said frame forwardly of said motor, a gear reduction means driven by said motor and operatively connected with said feed operating mechanisms for driving either at reduced speed, cuttings expulsion means beneath said motor, a transverse shaft disposed forwardly of the axes of said feed mechanisms having a clutch mechanism thereon for selectively engaging either of said feed operating mechanisms, and means for operating said cuttings expulsion means from said gear reduction means whereby the cuttings are forcibly discharged when either of said feed operating mechanisms is driven.
20. In a mining machine, a frame, a cutter bar extending forwardly from said frame and disposed centrally thereof, having a cutter chain mounted thereon, a motor at the rear end of said frame, a longitudinal shaft disposed above said cutter bar and connected with said motor, a pair of feed operating mechanisms mounted on transverse axes at opposite sides of said frame forwardly of said motor and the rear end of said cutter arm, a planetary gear reduction means driven by said longitudinal shaft and operatively connected with said feed operating mechanisms for driving either at reduced speed, a driving sprocket for said cutter chain disposed on a vertical axis between said gear reduction means and said motor, and gearing connections between said longitudinal shaft and said driving sprocket.
21. In a mining machine of the class described, the combination of a frame, a motor at the rear end thereof, a cutter bar extending from the forward end thereof and having a cutter chain mounted thereon, feed driving mechanism disposed forwardly of said motor comprising a pair of feed winding mechanisms disposed on transverse axes, each being associated with flexible draft means and operatively engaged through a transverse driving member disposed at the forward end of said frame and selectively driven by a planetary gear reduction device having gearing connections to a longitudinally disposed drive shaft driven by said motor, a chain driving sprocket disposed on a vertical axis rearwardly of the axis of said feed winding mechanisms and detachably driven through gearing connections from said drive shaft.
22. In a mining machine, a frame, a motor, a cutter bar having a cutter chain thereon, a sprocket operably connected with said mo-

tor for driving said chain, a transversely disposed feed driving member at one end of said frame, a pair of feed drums disposed on opposite sides of said frame on transverse axes disposed forwardly of the axis of said cutter chain sprocket, and clutch means concentric with said feed driving member for

selectively engaging either of said drums with said feed driving member.

Signed at Chicago, in the county of Cook ¹⁰ and State of Illinois, this 10th day of November, A. D. 1925.

THOMAS E. PRAY.
